UNITED STATES PATENT OFFICE.

GEORGE A. LAMP, OF ROCK ISLAND, ILLINOIS.

WIRE-BASKET SUPPORT.

1,386,878.

Specification of Letters Patent. Patented Aug. 9, 1921.

Application filed August 2, 1920. Serial No. 400,818.

To all whom it may concern:

Be it known that I, GEORGE A. LAMP, a citizen of the United States, residing at Rock Island, in the county of Rock Island, 5 State of Illinois, have invented certain new and useful Improvements in Wire-Basket Supports, of which the following is a description, reference being had to the accompanying drawing, and to the figures of 10 reference marked thereon.

This invention relates to wire basket supports, and more particularly to supports for wire baskets adapted for use in offices and similar places for holding papers and 15 other documents.

These paper containing baskets are either of the single type or are specially constructed to receive supporting wires or wire interconnections, whereby a plurality of baskets 20 may be held securely one above the other, that is, in a built-up unit. The main objection to the built-up baskets is that the connecting wires and supports are not capable of attachment to the ordinary single 25 type of basket in present day use.

An object of the present invention is to provide a simple and inexpensive type of support adapted for attachment to the ordinary type of wire basket of the single type 30 without the alteration of the basket in any particular and which support will hold the baskets in superimposed spaced relation.

Another object of the invention resides in providing a support of the above character 35 which will securely hold the baskets in proper position while permitting free access to the basket from all sides.

A further object of the invention resides in providing a device of the character described comprising a single wire constructed 40 and arranged to provide a basket support with integral attaching hooks spaced apart in a plane transverse to the support so that the corners of the baskets may project into 45 the spaces between the hooks, such arrangement, together with the resiliency of the wire constituting a means for locking the baskets in substantially rigid position.

Still another feature of this invention resides in constructing a support of the character described from a single wire, and in providing the same with the desired number 50 of hooks and strengthening twists.

These and other objects will in part be obvious and will in part be hereinafter more 55 fully disclosed.

In the drawings:

Figure 1 is a perspective view of four of the supports, holding three baskets in built-up position;

Fig. 2 is an enlarged view of one corner showing the support connecting with the basket;

Figs. 3 and 4 are detailed perspective views of modifications; and

Fig. 5 is a diagrammatic side view of a further modification.

In general the invention includes four of my supports having basket attaching means spaced along their length and adapted for 70 easy attachment to the ordinary type of wire basket used for holding papers and other light articles. Broadly the invention comprises any type of support having spaced basket attaching means, whether made of 75 wire or not.

In its preferred form, the invention as shown in detail in Fig. 1 comprises a single piece of wire of desired gage and strength folded upon itself to provide a closed top 80 1 and spaced parallel strands 2. At desired points these strands are twisted axially as at 3 to provide a suitable number of strengthening portions or zones. For the purpose of providing suitable supports for 85 the wire baskets 4, 5 and 6, the spaced strands 2—2 are each provided with portions bent upwardly as at 7, 8 and 9, which bent portions are preferably twisted but not necessarily so. These bent portions or 90 hooks are arranged in pairs in planes parallel with the longitudinal planes of the support, so that when they are assembled in position and the baskets attached thereto, as in Fig. 1, the hooks 7, 8 and 9 of each pair 95 will engage the wire strands of the baskets 4, 5 and 6 on each side of the corners thereof, which arrangement permits the corners of the baskets to substantially project into the spaces between the parallel strands. In this 100 manner the supports will not only hold the baskets in superimposed, spaced relation, but the natural resiliency of the supports will cause them to engage the baskets and lock the same in such position. The free ends 105 of the strands of each support are bent outwardly in suitable manner to provide supporting feet 10 and 11 which may or may not be provided with rubber sleeves 12.

In the modification shown in Fig. 3 a 110 support is shown having a single hook 13 at its upper end and a single hook 14 at its

lower extremity which is somewhat longer than usual so that it can engage over two strands of the wire of a basket. This construction enables a single basket to be supported from another basket lying on a desk. If desired, a basket may be provided with integral depending wires 15, 16, 17 and 18 at each corner, the lower extremities of which are bent into basket attaching hooks as in Fig. 4. In this construction, it is desirable to give the depending supporting wires a slight inward bend as at 19, 20, 21 and 22 to compensate for the outward flaring of the corners of the basket at the tops as 15 at 23.

It is also evident that it is within the scope of this invention to provide the supports with spaced hooks as in Fig. 5, which shows the opposite side of the wire with intermediate spaced basket hooks 24, 25 and 26 so that the supports may be reversed in position to support two baskets instead of three. These supports would, of course, have the intermediate twisted strengthening portions 20 29 and 30 and 31. It is also obvious that in lieu of these extra hooks 27 and 28 other article supporting bent portions may be provided.

It will be seen that a support of the above 30 character comprises a neat, simple and strong device for supporting baskets of the kind described. It is also clear that it has many advantages over other supports of similar character in that it can be quickly 35 and simply attached to wire baskets now in use without the alteration of the basket or of the support, or without the use of any implement or tool. Furthermore, these sup-

ports can be made up in various sizes and of different gages of wire, according to the 40 needs required.

Having thus described the invention, what I claim as new and desire to secure by Letters Patent is:—

1. A support for paper containing baskets and the like, comprising a strand of wire doubled to provide a closed fold at one end and supporting feet at the other, the strands of said wire being spaced and substantially parallel, said strands having a suitable number of bent portions to form basket attaching hooks, and intermediate portions twisted to provide strengthening portions.

2. A support for paper containing baskets and the like, comprising a single wire doubled on itself to provide a closed fold at one end and supporting feet at the other end, the strands of said wire being arranged in spaced parallelism, said strands at suitable points being formed with bent portions 55 to form basket attaching hooks.

3. A support for paper containing baskets and the like, comprising a single wire doubled on itself to form spaced strands, the free ends thereof forming supporting feet, said strands being twisted axially at certain points to provide strengthening zones, and formed intermediate said twisted portions with upwardly bent portions lying in the same plane and adapted to catch in 65 the strands of the wire basket so that the corners of said basket may project substantially into the space between the strands.

In testimony whereof, I affix my signature.

GEORGE A. LAMP.
